[57] CLAIM

The ornamental design for a hat gift box, as shown and described.

DESCRIPTION

FIG. 1 is a perspective, front and right side view of one embodiment of a hat gift box showing my new design;

FIG. 2 is a top plan view thereof;

FIG. 3 is a front elevational view thereof, the rear view being a mirror image;

FIG. 4 is a left side elevational view thereof;

FIG. 5 is an exploded, perspective view thereof showing the interior of the gift box;

FIG. 6 is a perspective, front and right side view of a second embodiment of a hat gift box showing my new design;

FIG. 7 is a top plan view thereof;

FIG. 8 is a front elevational view thereof, the rear view being a mirror image;

FIG. 9 is a left side elevational view thereof; and,

FIG. 10 is an exploded, perspective view thereof showing the interior of the gift box.

The bottom plan view of each embodiment is plain and unornamented.
